UNITED STATES PATENT OFFICE

MAX PAUL ERNST HOHN, OF DRESDEN, GERMANY, ASSIGNOR TO "UNIVERSELLE" CIGARETTENMASCHINENFABRIK J. C. MÜLLER & CO., OF DRESDEN, GERMANY

PACKING OF CIGARETTES

Application filed January 9, 1931, Serial No. 507,705, and in Germany September 10, 1930.

The object of the present invention is the turning of incorrectly-lying cigarettes during supply to the packing machine. For this purpose use is made of a property of cigarettes which have been pressed flat in known manner, namely that the two curved surfaces do not possess the same curvature. Owing to the overlapping of the paper on the seam side, a flatter curvature is formed on that side than on the opposite side which is provided with the printing.

According to the invention, the cigarettes are now conveyed flat past a feeler device, which explores the side lying upward for the time being and ascertains whether the flatter or the greater curvature lies upward, and if it is the flatter curvature i. e., the seam side, sets into operation an apparatus for turning the cigarettes into the opposite position. If desired, turning may also be effected when, inversely, the side of greater curvature is exposed, because, of course, it is substantially a matter of all the smooth surfaces being directed in one direction when the cigarettes are supplied to the packing machine, in order that they may be so placed in the packet that, at least in the upper layer, all the smooth surfaces, i. e. all the inscriptions face upward.

One construction of such an apparatus is shown diagrammatically by way of example in the accompanying drawing, in which

Figure 1 is a side elevation thereof,

Figure 2 is a cross-section through Figure 1,

Figure 3 shows a side elevation of a single feeler device taken from Figure 1, and illustrates the supply of current for the electrical connections.

The cigarettes 1 are placed flat and are carried on an endless conveyor chain, the links 2 of which are provided with troughs 3 for carrying the individual cigarettes. A feeler device is provided above the conveying apparatus; the said feeler device comprises a revolving shaft 4 carrying two discs 5 and 6 opposite one another, which are provided around their margins with trough-shaped notches 7. The said notches 7 are arranged at such intervals from one another that, with uniform rotation of the wheel and

uniform feed of the conveyor chain, the successive trough-shaped depressions of the conveyor chain 2 and of the discs 5 and 6 coincide with one another, so that the flat-lying cigarettes are secured or held by the discs 5 and 6 in their flat positions in the troughs of the chain. The two discs 5 and 6 are so arranged that the distance between their outer faces approximately corresponds to the width of the chain parts 2 (see Figure 2). The feeler device proper is situated between the two discs 5 and 6 and comprises a sleeve-shaped body 8, which is mounted fast on the shaft 4 and in which are provided a number of pins 9 corresponding to the number of troughs 7. The said pins carry collars 10 with which they bear against the inside of the sleeve-shaped body 8. The pins are pressed outwardly by springs 11 so that the collars bear against the body 8. On the outer end, the pins carry piston-shaped parts 12, to which are secured cylinders 14 by means of pins 13 passing transversely therethrough. Two feelers 15 and 16 are rigidly secured one on each side of the said cylinders by means of screws or the like. The feelers are provided at their lower ends with plate-shaped projections 17, which are adapted to the shape of the cigarettes and are situated at such a distance apart as to enter into the troughs 3 of the conveyor chain and to rest outwardly upon the cigarettes, that is to say, to rest upon the same close to their acute bends. Feeler pins 18 are mounted in the cylinders 14 and are moved in an outward direction from the cylinders by springs 19. The pins 18 carry on their free ends feeler plates 20. Within the cylinders the pins carry contact plates 21, which, as shown in Figure 2, project out of the cylinders 14 through slots in the same, and are provided with upwardly directed points. Contact plates 22 are provided on the cylinders, opposite the said point. On the cylinders 14, which consist of an electrically non-conducting material are also pins 23, inserted in the cylinders, which pins pass through the contact plates 22 and are electrically joined therewith. The said pins are each embraced by one end of a contact spring 24, the other

end of which is rolled round to form an elongated eye and embraces a pin 25. All the pins 25 of the different feeler devices are inserted in a metal plate 26, which is attached 5 to a disc 27 of insulating material. A conducting bar 28 passes through a hole in the said disc 27 and connects the disc 26 with a collector ring 29 of metal on a hub-shaped projection of the disc 27.

- 10 The current supply, as will be gathered more particularly from Figure 3, is effected in such a manner that one pole of the source of power is connected through a lead 30 by means of a contact spring to the shaft 4. 15 Thence the current passes through the sleeve 8, the pin 9, the pin 18, the contact 21, and, if a pair of the contacts 21, 22 is closed, through the latter, the pin 23, the lead 24, the pin 25, the disc 26, the lead 28, the collector ring 29 and through the lead 31 back again to the second pole.

The mode of operation of the device is accordingly as follows:—

- 20 The cigarettes are placed in the troughs 3 of the conveyor belt 2, and the latter moves forward uniformly in the direction of the arrow, Figure 1. At the same time, the exploring apparatus is rotated uniformly by the shaft 4 in the direction of the arrow, so 25 that the successive troughs of the chain and of the exploring apparatus are brought into coincidence with one another. The exploring apparatus bears against the upper side of the cigarette in the manner to be seen in 30 Figure 1. The two outer feelers 15 and 16 bear against the sides and adjust the entire cylinder 14, which is of course slidable in the sleeve 8, against the action of the spring 11, according to the height on the edges of the 35 cigarette in the trough. The middle feeler 20 then engages with the most curved portion of the cigarette, and according as to whether the curvature is greater or flatter, the middle pin 18 with the feeler 20 will be 40 displaced more or less with respect to the outer feelers 15 and 16. The result of this displacement is to move the contact pin 21, and the distance between the two contacts 21 and 22 is so proportioned that the difference 45 in curvature between the seam side and the smooth side of the cigarette is sufficient to move the contact pin 21 so far as to make contact. The making of contact is then utilized 50 for turning the incorrectly-lying cigarettes. Devices that are put into operation by a contact and effect the turning of incorrectly-lying cigarettes are known per se and consequently do not require detailed description.

- 55 In the example described, it is not a question as to how high the cigarette lies in the trough 2 itself, i. e. whether it lies on the bottom of the trough or whether, for example, a cavity is left between the bottom of the trough and the cigarette, because the clos-

ing of the contact only depends upon how far the middle feeler is displaced with respect to the outer feelers, that is to say, solely upon the actual curvature of the top side. Of course, however, other constructions may be 70 developed. Thus, for example, the shape of the troughs in the conveyor chain 2 may be adapted exactly to the greater curvature of the cigarette, in this case when the cigarette lies with its flatter curvature downward a 75 certain amount of clearance is left between the trough and cigarette, so that the cigarette actually lies higher and the contact may then be released through this higher position of the cigarette. 80

Since the greater curvature of the cigarette is on the printed side, the contact in the example shown will always be closed when the smooth side lies upward. In this case, therefore, it would be convenient to arrange the turning apparatus so that it remains inoperative when the current is closed, but comes into operation on the contrary, when it is interrupted.

Constructionally, of course, the device may 90 be executed in still other ways. For example, instead of arranging the feelers on revolving discs, they may also be arranged on endless bands, or also, instead of effecting the supply of cigarettes by a conveyor belt, 95 it may be effected by conveyor drums with trough-shaped recesses around the periphery, and the like. Also, in manufacturing the cigarettes, the curvature may intentionally 100 be made to differ somewhat more considerably on the two sides, in order to increase the effect of the device and to make it more certain in action.

I claim:—

1. A feeler device for detecting incorrectly-lying cigarettes during conveyance to a packing machine comprising a plurality of feelers adapted to be moved independently of each other and differently according to the curvature of the cigarettes, the difference in the movement of said feelers being used for controlling the turning of the cigarettes. 105

2. A feeler device for detecting incorrectly-lying cigarettes during conveyance to a packing machine comprising three feelers, two outer feelers thereof being commonly movable and bearing against the edges of the flat lying cigarettes, and the middle feeler being movable independently of the others and bearing on the highest part of the curvature of the cigarette, the difference in the movement of the middle feeler with respect to the outer feelers being utilized for controlling the turning of the cigarettes. 110 115 120

3. A device for detecting incorrectly-lying cigarettes during conveyance to a packing machine comprising feeler devices, a holder for said feeler devices, each of said feeler devices comprising a trough for holding the cigarette and a plurality of feelers adapted 125 130

to be moved differently according to the curvature of the cigarette the difference in the movement of said feelers controlling the turning of the cigarettes.

- 5 4. A device for detecting incorrectly-lying cigarettes during conveyance to a packing machine comprising feeler devices, a holder for said feeler devices movable in accordance with the conveyed cigarettes, the feeler devices exploring the freely-lying side of a cigarette supplied in the flat position and containing three feelers, two outer feelers being commonly movable and bearing against the edges of the flat-lying cigarettes, and the 10 middle feeler being movable independently of the others and bearing on the highest part of the curvature, a holding piece for the two

outer feelers of each feeler device guided in said holder and guiding the middle feeler, and means arranged on said holder and holding pieces for resiliently pressing said feelers against the cigarette, the difference in the 70 movement of the middle feeler with respect to the outer feeler controlling the turning of the cigarettes.

5. An apparatus in accordance with claim 4, in which the holding piece consists of an 75 electrically non-conducting material and carries a contact, against which, when the curved side of the cigarette is explored, bears a contact pin secured to the middle feeler.

In testimony whereof I have affixed my 80 signature.

MAX PAUL ERNST HOHN.
